(57) **CLAIM**

I claim the ornamental design for a vehicle antenna, as shown and described.

DESCRIPTION

FIG. 1 is a plan view of the design for a vehicle antenna.

FIG. 2 is a bottom view thereof.

FIG. 3 is a rear view thereof.

FIG. 4 is a front view thereof.

FIG. 5 is a right view thereof; and,

FIG. 6 is a left view thereof.

The broken lines in the figures depict environment only and form no part of the claimed design.

1 Claim, 2 Drawing Sheets(56)
